UNITED STATES PATENT OFFICE
CERTIFICATE OF CORRECTION

Design No. 184,001

Sidney H. Bradd, Jr., et al.

December 2, 1958

It is hereby certified that error appears in the above numbered patent requiring correction and that the said Letters Patent should read as corrected below.

In the grant, lines 1, 2, and 3, for "Sidney H. Bradd, Jr., of New York, and Robert J. Harper, of Scarsdale, New York, and John C. Lockwood, of Atlanta, Georgia," read -- Sidney H. Bradd, Jr., of New York, and Robert J. Harper, of Scarsdale, New York, and John C. Lockwood, of Atlanta, Georgia, assignors to Scripto, Inc., a corporation of Georgia, --; lines 13 and 14, for "Sidney H. Bradd, Jr., Robert J. Harper, and John C. Lockwood, their heirs" read -- Scripto, Inc., its successors --; in the heading to the drawing and specification, lines 3 and 4, for "Sidney H. Bradd, Jr., New York, and Robert J. Harper, Scarsdale, N. Y., and John C. Lockwood, Atlanta, Ga." read -- Sidney H. Bradd, Jr., New York, and Robert J. Harper, Scarsdale, N. Y., and John C. Lockwood, Atlanta, Ga., assignors to Scripto, Inc., a corporation of Georgia --.

Signed and sealed this 5th day of May 1959.
